UNITED STATES PATENT OFFICE

128,514

DESIGN FOR A HEAT EXCHANGER CORE UNIT

Fred M. Young, Racine, Wis.

Application November 4, 1940, Serial No. 96,287

Term of patent 14 years

To all whom it may concern:

Be it known that I, Fred M. Young, a citizen of the United States, residing at Racine, in the county of Racine and State of Wisconsin, have invented a new, original, and ornamental Design for Heat Exchanger Core Units, of which the following is a specification, reference being had to the accompanying drawing, forming a part thereof.

Fig. 1 is a perspective view of a heat exchanger core unit showing my new design;

Fig. 2 is a side elevational view thereof.

Fig. 3 is a rear elevational view thereof.

I claim:

The ornamental design for a heat exchanger core unit, as shown.

FRED M. YOUNG.
